Application filed July 21, 1931. Serial No. 40,618. Term of patent 14 years.

To all whom it may concern:

Be it known that we, JOHN G. H. LIEBEL and EDWIN S. FLARSHEIM, both citizens of the United States, and both residents of Cincinnati, in the county of Hamilton, State of Ohio, have invented a new, original, and ornamental Design for a Portable Cabinet Pedestal for Lamp Stands, of which the following is a specification, reference being had to the accompanying drawing, forming a part thereof.

The figure is a perspective view of the cabi-

The view being in perspective, the design detail displays more dominantly one side of the cabinet. The opposite or other sides, however, are substantially the same.

We claim:
